UNITED STATES PATENT OFFICE.

OSCAR BRUNNER, OF ST. LOUIS, MISSOURI.

CABINET LOCK.

Application filed May 9, 1924. Serial No. 711,991.

To all whom it may concern:

Be it known that I, OSCAR BRUNNER, a citizen of the United States, residing at St. Louis, Missouri, have invented a certain new and useful Improvement in Cabinet Locks, of which the following is a specification, such as will enable others skilled in the art to which it appertains to make and use the same.

10 My invention relates to the construction of cabinets provided with drawers, lockers, bins and the like, and consists in an improved locking mechanism for the drawers, etc.

15 The objects of my invention are to provide a single manipulative member adapted to engage substantially all of the drawers, etc. to provide a drawer equipped with the ordinary lock which also locks such operating member, and to render access to the operating member impossible except when the drawer is open.

In the accompanying drawings, which illustrate my invention,—

20 Figure 1 is a top view of a selected cabinet with the top removed.

Figure 2 is a front elevation.

25 Figure 3 is a vertical longitudinal section taken immediately in the rear of the drawers.

30 Figures 4 and 5 are vertical transverse sections taken on lines 4-4 and 5-5, respectively, of Figure 3.

35 Figure 6 is a detail vertical transverse section on an enlarged scale.

The cabinet is provided with the usual top 1, sides 2, and back 3. A fascia or rail 4 extends along the bottom of the top near the front of the latter. The cabinet has 40 drawers, 6, 7, 8, 9 and 10 resting upon slides 11, 12, 13, 14 and 15, respectively, and is also provided with bins 16 each adapted to tilt at its lower front edge so as to open forwardly of the cabinet.

45 Near the rear wall 3 of the cabinet and slidably longitudinally thereof is a frame member 17, the lower horizontal bar of which rests upon drawer slides 13 and 15, and the upper bar of which passes beneath 50 one of the slides 11. The intermediate bar of the frame passes over one of slides 12 and under one of slides 14. It will be seen that frame 17 is free to move to the right or left but cannot move upwardly or downwardly. If desired, one or more brackets 18 may be secured to the cabinet near wall 3 to

guide or support frame 17. These brackets may be used either in addition to or as substitutes for the slide elements which engage the frame. The member 17 is provided with 60 clips or other projecting elements 19 having vertical faces adapted to engage corresponding elements 20 provided on drawers 7, 8, 9 and 10 when aligned therewith. Member 17 is also provided with projecting elements 65 19^a adapted to present horizontal engaging surfaces to corresponding elements 20^a projecting from the lower rear edges of bin 16 when aligned therewith, thereby positively preventing tilting movement of the bin. 70

The locking member 17 may be moved transversely of its supporting slides and longitudinally of the cabinet by means of a lever 21 pivoted at 22 to the lower surface of the cabinet top and terminating at its 75 forward end in a downwardly offset projection 23 which extends into an arcuate recess 24 provided in the inner face of rail 4.

The upper left hand drawer 6 of the 80 cabinet is not engaged by locking member 17 but is provided with an individual lock 25 adapted to be operated by a key in the usual manner. The lock bolt 26, when projected, extends upwardly to engage a lock 85 plate 27 on the upper face of recess 24 in rail 4. Projection 23 on lever 21 is recessed to receive bolt 26 when projected and it will be understood that when the lever is in the position shown in full lines in Figure 90 1 and when drawer 6 is closed and its lock bolt projected as indicated in Figure 6, the lever will be positively held in the position to lock the drawers and bins as described. It will be noted that drawer 6 can be locked 95 with lever 21 in the position shown in dotted lines in Figure 1, in which case the remaining drawers and bins are unlocked.

Obviously, lever 21 may be located elsewhere than shown, and, if desired, may be 100 provided with a lock independently of a drawer or bin. Such variations and other modifications of my construction are within the spirit of my invention as claimed.

I claim:

1. In a cabinet, a sliding drawer, a tilting bin, a member at the rear of said cabinet movable in a straight line transversely of said drawer and bin and having a vertical surface adapted to engage said drawer to 110 prevent its withdrawal and having a horizontal surface adapted to engage said bin

to prevent its tilting, and locking means at the front of said cabinet for preventing movement of said member.

2. In a cabinet, a plurality of drawers, a movable member in the rear of the cabinet for engaging said drawers to prevent their being opened, manually operated means at the front of the cabinet for moving said member to disengage said drawers, another drawer, the front of which when the drawer is closed prevents access to said means, and a lock for said last-mentioned drawer adapted to lock said means also.

3. In a cabinet, a plurality of drawers, a movable member in the rear of the cabinet for engaging said drawers to prevent their being opened, a lever pivoted between its ends to the underside of the top of the cabinet, connected at its rear end to said member and with its forward end terminating near the front of the cabinet, a drawer not engaged by said member, a lock plate on the cabinet a lock in the front wall of said drawer, the bolt of which lock moves vertically to engage said lock plate, and also engages said lever to prevent its return when said lever has moved said member to functioning position.

4. In a cabinet, drawer slides, drawers therein, a tilting bin, the rear wall of which rises when the bin is opened, a frame supported by some of said slides, held against lifting by others of said slides and movable transversely of said slides, vertical elements on said drawers, horizontal elements on said bins, elements on said frame adapted to engage said drawer and bin elements to prevent opening of the drawers and bins, and means for moving said frame across said slides to engage or disengage said elements.

5. In a cabinet, a top, drawers, a lock on the front of one of said drawers, a locking member for the drawers in the rear of said cabinet, a member operating lever pivoted to the lower face of the top of said cabinet, with one arm terminating near the front thereof and offset downwardly to afford a finger hold, a front rail on said top recessed to receive said offset end, a lock plate in said recess to receive the bolt of said lock, said offset end being recessed to receive said bolt when said lever is moved to position to cause said member to lock said drawers.

In testimony whereof I hereunto affix my signature this 1st day of May, 1924.

OSCAR BRUNNER.
